OR D 19,061 EX

DESIGN.

—o—

T. K. BENTON.

WATCH CASE.

No. 19,061.

Patented Apr. 30, 1889.

UNITED STATES PATENT OFFICE.

THOMAS K. BENTON, OF SUMMIT, NEW JERSEY, ASSIGNOR TO THE COUR-
VOISIER, WILCOX MANUFACTURING COMPANY, OF NEW YORK, N. Y.

DESIGN FOR A WATCH-CASE.

SPECIFICATION forming part of Design No. 19,061, dated April 30, 1889.

Application filed March 7, 1889. Serial No. 302,332. Term of patent 7 years.

To all whom it may concern:

Be it known that I, THOMAS K. BENTON, a citizen of the United States, residing at Summit, in the county of Union and State of New Jersey, have invented and produced a new and original Design for Watch-Cases, of which the following is a specification, reference being had to the accompanying photograph, forming part hereof, which represents 10 a back or face view of my new design for watch-cases.

This invention relates to a new configuration of the edge of a watch-case, and consists of the new bracketed ornaments applied 15 to the edge of a watch-case; and the leading features of the design consist, first, in an open-work bracket and a connecting open-work brace, and, second, of open-work brackets near the stem and open-work brackets and a connecting open-work brace opposite the stem.

In the photograph, the letter *a* represents the body of the watch-case. *b* is the stem.

On each side of the stem the watch-case *a* is provided with projecting brackets *d*, which are truss-shaped and open, as shown. Opposite to the stem *b* the edge of the watch-case is provided with open truss-shaped brackets *e*, between which is an open-work brace, *f*, having curled ends and internal open-work filling, as shown. 25

I claim—

1. The design for a watch-case, the same consisting of the open-work brackets *e* and connecting open-work brace *f* between the brackets *e*, substantially as shown. 30

2. The design for a watch-case, the same consisting of the open-work brackets *d* near the stem and of the open-work brackets *e* and connecting open-work brace *f* opposite the stem, substantially as shown.

THOMAS K. BENTON.
